United States Patent Office

Des. 201,975
Patented Aug. 17, 1965

201,975

TOY BANK

Thomas E. Brown, Woonsocket, R.I., assignor to Rexall Drug and Chemical Company, Los Angeles, Calif., a corporation of Delaware

Filed Mar. 1, 1965, Ser. No. 84,019

Term of patent 14 years

(Cl. D34—11)

FIG. 1

FIG. 2

FIG. 3

FIG. 4

FIG. 5

FIG. 6

The dominant features of my design reside in the portion shown in full lines.

I claim:

The ornamental design for a toy bank, substantially as shown and described.
